MACHINE AND METHOD FOR
MAKING BRICKS

Herman M. McCAN, El Cajon, Calif.

Application September 6, 1946, Serial No. 695,069

5 Claims. (Cl. 25—105)

1 The present invention relates to brick making machinery and is more particularly concerned with an apparatus and method for making a concrete slab into bricks.

The primary object of the invention is to produce a novel method of cutting concrete bricks and an apparatus to carry the same into effect.

Another object of the invention is to provide a novel and efficient apparatus of the character referred to of simple and durable construction which is powered by electric motor.

A further object of the invention is to provide a device of the character referred to of simpler and more compact construction than prior devices.

With the foregoing and other objects and advantages in view the invention consists of the novel construction and arrangement of parts for the apparatus, and a novel process for doing the work, as hereinafter described and claimed.

In the accompanying drawings illustrating the construction of said apparatus,

Figure 1 is a front elevation of the longitudinally movable cutting machine.

Figure 2 is a top plan view thereof, partly in section.

Figure 3 is an end elevation thereof.

Figure 4 is a top plan view of the cross cutting device.

Figure 5 is a fragmentary side elevation of the cross cutting device.

Figure 6 is fragmentary longitudinal section of the cutting disc shaft bearing of the longitudinal cutter.

Figure 7 is a vertical transverse section through the said shaft exteriorly of one end sill of the apparatus frame.

Like numerals, as used in the description and drawings, designate the same parts in the construction of the apparatus.

The frame of the longitudinal cutter A comprises upper and lower longitudinal sills 10 and 11, upper and lower end sills 12 and 13 and vertical columns 14, all connected and trussed to form an elongated rectangular frame, the top of which is covered by a flat top 15. This frame is designed to be mounted on a track comprising a pair of spaced-apart, parallel rails 16, suitably spaced to accommodate the concrete slab to be made and laid out on a specially prepared and level work surface between the rails, preparatory to cutting it into bricks.

The said rails are preferably constructed of angle iron and inversely disposed angle iron run-

ners 17 are attached to the lower ends of the upright columns 14.

Mounted in vertical bearing slots 18 in the lower end sills 13 and approximately midway the said columns is a rotatable shaft 19 on which are a plurality of discs 20 having cutting edges. These discs are arranged in groups and suitably spaced apart, both as to grouping and position in the group. Separating the several groups of cutting discs are trusses 21. The shaft 19 passes through them. Between the discs are spacer collars 22, and similar collars space the groups from the said trusses, as well as the end sills.

Mounted on the projecting end of shaft 19 is a sprocket 23 which is driven by sprocket chain 24 from a smaller sprocket 25 mounted on the outer end of a rotatable stud shaft 26. This shaft is supported in a bracket 27 mounted on the top 15 of the machine.

Between the bracket and sprocket is a large gear 28 to which the sprocket is secured so as to be rotated thereby. Said gear meshes with a reduction pinion 29 which is mounted revolvably on a stud shaft supported in the same bracket but suitably positioned in relation to the first mentioned stud shaft. The ratio of said intermeshing reduction gears is preferably 100 to 1. Mounted on the shaft with the pinion 29 and rotatable therewith is a pulley 30 which is connected by belt 31 to a smaller pulley 32 on the drive shaft of a motor 13, preferably $\frac{1}{2}$ H. P. Thus, it will be observed, the cutter discs can be operated by motor and controlled by a switch. Also it will be noted that the cutting discs, as normally set, have their cutting edges in close proximity to the ground and they are maintained in this position by adjusting movement of shaft 19 in its bearings, as heretofore explained.

The rails 16 on which the above described machine is designed to travel, are spaced apart to suit the width of the slab of concrete to be poured, as it will be made on the flat working surface between the rails and extend as far as desired. When the concrete is poured and spread sufficiently deep to meet requirements, a heavy roller is passed over it until it is rolled down to the angle iron tracks. As these are preferably about 2 inches high, they fix the thickness of the slab. It is now ready for cutting into longitudinal sections by the use of the aforesaid machine. Any size of brick can be cut by simply changing the size of the spacers 22 and the bricks produced will be of the solid type.

The slab having been cut longitudinally the 55 operation is now ready for cross cutting. For

this step in the process a hand operated transverse cutter B is used.

It comprises a frame of a plurality of spaced parallel bars 34, approximately as long as the width of tracks 16. These bars are mounted on two angle iron runners 35 designed to travel on said tracks.

Mounted on said frame is a gang of five cutting discs 36, similar to discs 20 of the main machine. These are mounted on a rotatable shaft 37 and spaced by spacer collars 38. Said shaft is rotatably mounted in a hand drawn yoke 39, provided with a tongue and forward handle bar 40. Intermediate said handle bar and the yoke 39 is a perpendicular bar 41 with a handle bar 42 on top for lifting said discs when said frame is moved along said rails. The bars 34 of the frame of this device are arranged so that each cutting disc travels between two contiguous bars, when the yoke is pushed across the slab of concrete. To facilitate this second step in the operation, the tracks 16 are marked off and notched. This obviates measurements each time the cross cutting is moved along. Further to facilitate the operation, the surface of the runway is greased in advance to prevent the finished bricks from sticking. If desired, the brick may be left on the floor of the runway and cured under water.

As different embodiments may be made of the mechanical features of this inventive concept and modifications may be made in the embodiment hereinbefore shown and described, it will be understood that the matter herein is to be interpreted as illustrative merely, and not in a limiting sense.

What I claim is:

1. Brick making apparatus comprising a pair of fixed, parallel rails, a flat work surface between said rails, a longitudinal cutter and a transverse cutter supported on said rails for movement longitudinally thereof, said longitudinal cutter comprising a rectangular frame supported at its ends on said rails and extending thereabove, a shaft journaled in the lower portion of said frame and extending transversely across the space between said rails, a plurality of spaced-apart cutting discs secured on said shaft, and disc-driving means carried by said frame and drivingly connected with said shaft, and said transverse cutter comprising a rectangular frame supported at its ends on said rails and including a plurality of spaced-apart, parallel bars providing guide slots extending transversely of the space between said rails, a yoke operatively positioned above said bars and having a tongue extending outwardly therefrom, a shaft journaled in said yoke and extending transversely across said bars, a plurality of discs on said shaft movable in the guide slots between said bars, and a handle secured to said yoke for lifting the discs carried thereby.

2. Brick making apparatus comprising a pair of fixed, parallel rails, a flat, fixed work surface between said rails adapted to receive a slab of brick material, and a longitudinal cutter and a transverse cutter supported on said rails and movable therealong to divide said slab longitudinally and transversely into separable bricks, each of said cutters comprising a frame supported at its ends on said rails and a plurality of spaced-apart cutting discs carried by the corresponding frame

and movable through the space between said rails substantially in contact with said work surface.

3. Brick making apparatus comprising a pair of fixed, substantially parallel rails of a height substantially equal to the thickness of the bricks to be made, a flat work surface extending between said rails at the bottoms thereof to support a slab of brick material, the top surface of which is substantially flush with the tops of said rails, and a longitudinal cutter and a transverse cutter supported on and movable along said rails and operative to divide said slab longitudinally and transversely into separable bricks, said longitudinal cutter comprising a frame supported at its ends on said rails, a shaft journaled in said frame and extending transversely across the space between said rails, and a plurality of spaced-apart cutting discs secured on said shaft, and said transverse cutter comprising a frame supported at its ends on said rails and providing a plurality of spaced-apart guide slots extending transversely across the space between said rails, a manually-movable yoke movable along said frame from one of said rails to the other, a shaft carried by said yoke extending transversely of said frame, and a plurality of cutting discs carried by said shaft and projecting through said guide slots.

4. The method of manufacturing bricks which comprises forming a slab of brick material on a fixed working surface between fixed parallel rails, leveling the upper surface of said slab to a plane including the tops of said rails, moving a cutter along said rails to impress a plurality of longitudinally-extending, spaced, parallel cuts in said slab, and moving a second cutter along said rails to successive positions therealong and transversely of the space between said rails at the successive positions to impress a plurality of spaced, parallel transverse cuts in said slab to thereby divide said slab into a plurality of separable bricks.

5. The method of manufacturing bricks which comprises preparing a slab-receiving space on a fixed work table between a pair of parallel, fixed rails by coating the slab-contacting surfaces with an anti-adhesive material, forming a slab of predetermined thickness in said space, moving a longitudinal cutter along said rails to impress a plurality of spaced, parallel cuts extending longitudinally of said slab, and moving a transverse cutter along said rails and transversely of the space therebetween to impress a plurality of spaced, parallel cuts extending transversely of said slab to thereby divide said slab into a plurality of separable bricks.
